UNITED STATES PATENT OFFICE.

CHARLES C. SPENGLER, OF ROCKFORD, ILLINOIS.

FILING DEVICE.

SPECIFICATION forming part of Letters Patent No. 784,812, dated March 14, 1905.

Application filed October 12, 1904. Serial No. 228,242.

To all whom it may concern:

Be it known that I, CHARLES C. SPENGLER, a citizen of the United States, residing at Rockford, in the county of Winnebago and State of Illinois, have invented certain new and useful 5 Improvements in Filing Devices, of which the following is a specification.

This invention relates to document and card files, and refers particularly to an improved 10 means for locking the followers of such files.

The object of the invention is the production 15 of a follower-lock composed of few and simple parts, one in which the locking action is positive and secure, and which may positively be engaged or disengaged at the will of the operator.

In the accompanying drawings, Figure 1 is 20 a longitudinal vertical section through a document-file, showing my improved locking device applied to the follower. Fig. 2 is a transverse vertical section through a file, showing the follower in rear elevation and said locking means. In this view the lock is in its unlocked position. Fig. 3 is a view similar to 25 the last preceding figure, showing the follower locked in position. Fig. 4 is a perspective view of the bracket upon which the follower is supported.

In the application of my invention to a filing-cabinet I provide the usual file case or 30 drawer 1, having the front 2, the sides 3, the rear end 4, and the bottom 5. The bottom has the usual longitudinal opening 6, with the guide-rod 7 therein. The guide-rod 7 is secured with relation to the filing-case by aligned 35 openings 8 in the front and rear ends of the case, within which openings the guide-rod lies. The follower 9 is adapted to be moved longitudinally of the filing-case, being mounted 40 upon the guide-rod by means of a bracket 10, which now will be described.

The bracket 10 comprises an attaching-plate 11, provided with suitable openings for screws 12, by means of which the follower is secured 45 to said bracket. Two ears 13 and 14 extend downwardly from the attaching-plate 11 and into the opening 6 in the bottom 5. The ear 13 is formed from a portion punched out of the plate 10 and bent as shown in Figs. 1 and 50 4. The ear 14, which also is integral with the

plate 10, is doubled, being bent upwardly to form a loop 15 between the two sides of said ear 14. The ear 13 and the two sides of the ear 14 are provided with aligned openings 16, through which the guide-rod 7 extends. A 55 locking-lever 17, adapted to be loosely mounted on the guide-rod 7 within the loop 15 by means of the pivotal opening 18 therein, is provided with a cam 19, formed eccentric with said opening 18, also with an offset thumb- 60 ledge 20, by means of which latter the lever is grasped to be oscillated. The locking-lever 17 is adapted to lie within the loop 15 with the guide-rod 7 extending through its pivotal opening 18 and with its cam 19 adjacent to 65 the bottom of the loop 15. When the lever 17 is in the position indicated in Fig. 2, the cam 19 is free from the bottom of the loop 15, and said lever is loose upon the rod 7; but when the lever is moved into position it is 70 shown to occupy in Fig. 3 the cam 19 impinges upon the bottom of said loop 15 and forces the guide-rod 7 into frictional engagement with the walls of the openings 16. When the lever is in this position, the frictional engagement 75 between the ears 13 and 14 and the guide-rod 7 is sufficient to prevent the movement of the follower upon the said rod.

In operation the follower is unlocked by 80 moving the locking-lever 17 into position as shown in Fig. 2. When the lever is in this position, the follower may be moved freely upon the guide-rod 7. The follower remains unlocked until the lever 17 is thrown into the position indicated in Fig. 3, in which position 85 the cam 19, engaging the closed end portion of the loop 15, causes the guide-rod 7 to contact the walls of the openings 16 with sufficient pressure to prevent movement of the follower with reference to said guide-rod. 90

My invention is not restricted to the particular construction and arrangement of parts herein shown and described, as such construction and arrangement may be changed or modified by those skilled in the art without departing from the spirit and scope of the invention. 95

I claim as my invention—

1. In a lock for followers, in combination, a guide-rod; a follower; and a locking-lever 100

pivotedly mounted upon said guide-rod and adapted to hold the guide-rod and the follower in frictional engagement with each other.

2. In a lock for followers, in combination, 5 a guide-rod; a follower; a cam rotatable upon said guide-rod and adapted to move said follower with relation to said guide-rod to cause a frictional engagement between said parts; and a lever for moving said cam.

10 3. In a lock for followers, in combination, a guide-rod; a follower having two bearing-points upon said guide-rod; a cam pivotally mounted on said guide-rod between said bearing-points and adapted to cause a frictional engagement between said guide-rod and said bearing-points; and a lever for moving 15 said cam.

4. In a lock for followers, in combination, a guide-rod; a follower having two bearing-points upon said guide-rod; a cam pivotally mounted on said guide-rod and adapted to engage a portion of said follower between 20 said bearing-points to cause a frictional engagement between said guide-rod and said bearing-points; and a lever for moving 25 said cam.

5. In a lock for followers, in combination, a guide-rod; a follower having two perforated ears adapted to receive said guide-rod; a cam 30 pivotally mounted on said guide-rod and adapted to impinge upon said follower to cause a frictional engagement between said guide-rod and said ears; and a lever for moving said cam.

35 6. In a lock for followers, in combination, a guide-rod; a follower having two perforated ears adapted to receive said guide-rod; a cam pivotally mounted on said guide-rod between said ears and adapted to engage a 40 portion of said follower to cause a frictional

engagement between said guide-rod and said ears; and a locking-lever for moving said cam.

7. In a lock for followers, in combination, a guide-rod; a follower having two perforated ears adapted to receive said guide-rod, 45 one of which ears is doubled to form a loop; and a locking-lever pivotally mounted upon said guide-rod within said loop, said lever having a cam adapted to impinge upon said loop to cause a frictional engagement between 50 said guide-rod and said ears.

8. In a lock for followers, in combination, a follower; two perforated ears fixed to the lower edge of said follower and adapted to receive a guide-rod; a cam rotatable upon said 55 guide-rod for causing a frictional engagement between one of said ears and the guide-rod; and a lever for moving said cam.

9. In a lock for followers, in combination, a guide-rod; a follower; two perforated ears 60 fixed with relation to and extending downwardly from said follower, one of said ears having an angular portion; a cam rotatable upon said guide-rod for causing a frictional engagement between the guide-rod and said 65 angular portion; and a lever for moving said cam.

10. In a lock for followers, in combination, a guide-rod; a follower; a plate adapted to be attached to the lower edge of said follower; 70 two perforated ears integral with said plate and extending downwardly therefrom; a cam rotatable upon said guide-rod for causing a frictional engagement between said guide-rod and one of said ears; and a lever for moving 75 said cam.
